UNITED STATES PATENT OFFICE.

JAMES B. ROBINSON, OF WASHINGTON, DISTRICT OF COLUMBIA.

HYDROCARBON BURNER.

Application filed December 8, 1923. Serial No. 679,358.

This invention relates to hydrocarbon burners, and more particularly to that type which is adapted for use in domestic or commercial furnaces, although it will be obvious 5 that the features herein described may be readily applied in various other connections and for purposes other than the heating of furnaces.

One of the objects of the present invention is to provide not only an inexpensive 10 and simply constructed burner, but one which may be readily and rapidly installed without materially altering the construction of the furnace, stove or other heating unit in 15 which it is placed. In fact the majority of installations of this burner will require no alteration of the furnace at all.

In many of the furnace heaters now on 20 the market it is necessary to utilize a fan blower or some other forced draft mechanism operated by an electric or other motor which, 25 of course, materially affects the cost of operation, and it is, therefore, another object of this invention to provide a device operable and controlled by the natural draft through 30 the furnace, thus dispensing with unnecessary and costly apparatus.

Still another object of the invention is the 35 provision of a hydrocarbon burner with its parts so located and proportioned that there is obtained a flame of constant and uniform dimensions without any flickering such as would produce back firing.

Further objects of the invention will appear 40 as the following specific description is read in connection with the accompanying drawings, which form a part of this application, and in which:

Figure 1 is a vertical sectional view showing 45 the burner mounted in a furnace;

Figure 2 is a horizontal sectional view taken through the furnace showing the burner in plan and with parts broken away;

Figure 3 is a vertical sectional view taken 50 on the line 3—3 of Figure 1.

In the drawings, 1 indicates the wall of a furnace which may be of any type or construction and 2 indicates the fire box thereof. These parts are illustrated diagrammatically and are merely utilized for the 55 purpose of illustrating one use of the present invention and should not be construed as forming any part of the invention except as they are necessary for the support and association of the burner in this particular construction.

In mounting my burner in an ordinary domestic furnace the air tube or conduit is preferably placed in the slice door opening or in the fire door opening, although it will 60 be obvious that an opening may be made in any part of the wall of the furnace where convenient and the air tube or conduit inserted therein.

This air tube or conduit is generally indicated at 3 and is shown supplied with an elbow 4 at its inner end which is integral. In practice, however, the air conduit or tube 3 will probably be made of ordinary 3 inch pipe, to the inner end of which is screwed an 70 ordinary 3 inch elbow. This practice permits of the use of stock material and naturally cheapens the cost of installation.

The outer end of the air tube or conduit is somewhat reduced in diameter transversely 75 to its longitudinal axes by pinching in the upper and lower sides thereof as shown at 5 so as to provide in effect a pocket 6 which prevents unvaporized fuel from flowing out the inlet end. This reduced end is mounted 80 in an opening 7 in the furnace wall 1 so that the inner or discharge end of the air tube or conduit is located at the approximate center of the fire box 2.

As shown, the elbow 4 depends from the 85 body of the tube a short distance and located below the open discharge end of the elbow is a deflecting plate or pan 8 supported by a rod 9 secured to the upper inner surface of the elbow in any suitable manner. 90

At 10 I have shown a supply tank of any suitable character and dimensions to which is connected a feed pipe 11 having located therein the valves 12 and 13 to be hereinafter described. Connected to the feed pipe 11 95 which is of relatively small diameter is a pipe 14 which I shall call the supply and retort pipe, which after passing through the furnace wall as shown, extends along parallel to but in spaced relation with the air 100 tube 3 on one side thereof, and then extends around the elbow to the opposite side of the tube 3 where it is gradually elevated and terminates above the tube 3 intermediate the ends of the latter. The retort tube is of 105 relatively large diameter and has connected to its terminal end a short discharge pipe 15 which extends into the air conduit 3 and is supplied at its end with a discharge nozzle 16 located approximately centrally in the air 110 conduit. This discharge pipe 15 and the nozzle are of substantially the same diameter

as the feed pipe 11 and in practice I have found that an $\frac{1}{8}$ inch feed pipe and an $\frac{1}{8}$ inch discharge pipe are of correct dimensions when employed with a $\frac{3}{4}$ inch retort pipe.

Connected to the feed pipe 11 between the tank 10 and the regulating valve 12 is a small pipe 17 having a valve 18 therein and provided with a discharge nozzle 19 extended into the conduit 3 and arranged to discharge small quantities of oil upon the lower inner surface of the conduit 3 at or adjacent the point of connection of the elbow 4 with said conduit. This small quantity of oil which is discharged from the nozzle 19 will act in the capacity of a pilot burner when the tube 3 is heated and will be sufficient to maintain a proper vaporizing heat until the main burner is again utilized.

The valve 12 is employed in the present instance to regulate the quantity of oil fed to the retort pipe 14 or of course, may be utilized to cut off the supply to said pipe. I, however, provide an additional valve 13 which is automatic in its operation as follows:

The pan or deflector 8 has communicating with the interior thereof a small discharge pipe 20 which leads out of the furnace and is arranged to discharge in a bucket 21 pivoted upon a bracket 22 and provided with an extending lip 23 which is engaged by a depending finger 24 carried by and formed rigid with the valve lever 25 of the valve 13. This lever is provided with an adjustable weight 26 and under normal conditions the arm 25 is supported in substantially horizontal position with the valve 13 open. When the bucket fills the weight of the oil therein tilts the same against the pressure of the weight 26 until the lip 23 is thrown out of the path of the finger 24, at which time the weight 26 will cause the arm 25 to drop and thus close the valve.

This control is provided for the purpose of taking care of any unconsumed fuel that falls into the deflector 8 and is not vaporized by the heat from the burner.

It will be noticed that the retort pipe from its point of connection with the feed pipe 11 is extended on an incline to its point of connection with the discharge pipe 15, and that this pipe is made considerably larger than the feed pipe 11 so as to, not only provide a relatively large heating surface, but to hold a considerable quantity of oil which slowly moves up the incline so as to be subjected for the longest possible period to the heat from the burner. By this construction I have been enabled to obtain a thorough vaporization of the liquid fuel before it reaches the discharge pipe 15 and nozzle. Of course it is understood that should any raw or unvaporized fuel be discharged from the nozzle 16 during operation

of the burner at full capacity the regulating valve can be manipulated to cut down the supply to the retort tube and thus only enough oil will be fed to the retort tube which the heat of the burner can properly vaporize. It has been found in practice, however, that utilizing an $\frac{1}{8}$ inch feed tube and a $\frac{3}{4}$ inch retort tube 14, and inclining the latter at the proper angle, that the valve 12 can be left fully open under almost all conditions where maximum heating is required.

In order that the combustible mixture of air and vaporized fuel is properly distributed over the deflector I preferably arrange within the outlet end of the elbow a baffle 27 which in the present instance is secured to the deflector supporting rod 9 and is arranged diagonally across the mouth of the elbow with its major portion arranged in the path of the heaviest portion of the combustible mixture. This baffle not only perfectly distributes the combustible mixture but has the effect of slightly retarding the combustible gases so that they are further heated before being discharged through the restricted opening 28 between the lower end of the elbow and the distributing pan 8.

It will be noted that I have supported the distributing pan upon the lower end of the rod 9 which is threaded so as to receive limiting and locking nuts 29 and 30, thus providing for an adjustment of the pan to regulate the size of the opening 28.

In the operation of the device the burner is preferably started by heating the tube or conduit 3 in any suitable manner. This may be done by placing a small quantity of oil soaked waste or paper in the inlet end of the conduit 3. At the same time a small quantity of oil is allowed to pass through the discharge pipe 15 and drip from the nozzle 16. The heat generated by the ignition of the oil soaked waste or paper vaporizes the oil in the discharge pipe 15 and thereby produces a gas which is discharged from the nozzle and mixed with the air passing through the conduit 3, thus producing a combustible mixture which is ignited at the opening 28. This combustible mixture striking upon the deflector plate is deflected in all directions thus producing a circular flame which impinges directly against the retort tube 14, thus vaporizing the fuel therein. After the burner has been operating in this manner for a few minutes the valve 12 may be opened fully and the burner operated at full capacity. When the burner is thus operated the valve 18 is closed and the supply of fuel to the pilot thus cut off. When the burner is operating at full or reduced capacities or even when merely operated by the fuel from the pilot the draft through the furnace will be sufficient to cause a rapid flow of air through the conduit 3 and produce

a thorough intermingling of the air with the vaporized fuel atoms. If the valve 18 be turned on before the heat has departed from the tube the oil dripping from the nozzle 5 19 will be immediately vaporized and will produce sufficient heat at the burner opening 28 and in the retort tube to keep the latter heated sufficient to vaporize the initial small quantity of oil which is admitted when 10 the main fuel supply is turned on. In using the burner in domestic furnaces the main fuel supply may be cut off at night and the pilot turned on, and this small quantity of fuel will be sufficient to maintain the proper heat 15 for starting up the main supply in the morning, and in fact is sufficient to keep a temperature of approximately 100° F. in a hot water boiler, throughout the night.

It will thus be seen that I have provided 20 a very simple and inexpensive construction which may be conveniently and cheaply installed and which is particularly adapted for use in domestic furnaces now in use. It has been found in practice that the illustrated 25 type of burner may be utilized in lieu of coal and at a considerably reduced operating expenditure, as it is constructed and arranged to operate with the heavier hydro-carbon oils.

30 I claim:—

1. In a burner, a horizontally disposed

air tube having a depending discharge end, a fuel nozzle located within the horizontal portion of the air tube, a source of fuel supply including a small feed pipe, and a large 35 retort tube compared to the feed pipe connecting the feed pipe and said nozzle and arranged wholly above the discharge end of the air tube and extending around said discharge end so as to be subjected to the direct heat of 40 the burner, said retort tube being inclined from its connection with the feed pipe to its connection with the nozzle so as to retard the fuel flow therein.

2. In a burner, an air tube, means for 45 producing a combustible mixture therein, a deflector supporting rod carried by the air tube, a deflector supported thereon and covering but spaced away from the discharge end of the air tube and a baffle carried by 50 said rod and arranged within the discharge end of the air tube.

3. In a burner, an air tube, means for 55 producing a combustible mixture therein, a deflector supporting rod carried by the air tube, a deflector supported thereon and covering but spaced away from the discharge end of the air tube, and a baffle arranged diagonally within the discharge end of the air tube and supported upon said rod. 60

In testimony whereof I affix my signature.
JAMES B. ROBINSON.
